ATTORNEY

UNITED STATES PATENT OFFICE.

GEORGE BENDER, OF HOBOKEN, NEW JERSEY.

ZITHERN.

SPECIFICATION forming part of Letters Patent No. 286,524, dated October 9, 1883.

Application filed April 30, 1883. (No model.)

To all whom it may concern:

Be it known that I, GEORGE BENDER, of Hoboken, in the county of Hudson and State of New Jersey, have invented certain new and useful Improvements in Zitherns, of which the following is a specification.

The common zithern heretofore in general use has, owing to the small volume of sound and its sharp tone, only a limited application, and is but little adapted for concert purposes. Attempts have been made to impart to it a greater volume of tone, but without success.

The object of this invention is to provide a zithern having a full resonant tone, which can be used with advantage for concert purposes; and the invention consists of a zithern of peculiar construction, as hereinafter described.

In the accompanying drawings, Figure 1 represents a plan view, and Fig. 2 a vertical transverse section, of this improved zithern on line *x x* of Fig. 1.

Similar letters of reference indicate corresponding parts.

The body of this improved zithern is supported on legs *A*, and consists of two separable parts, *B* and *C*. The upper part, *B*, is composed of a string-board, *b*, having an opening, *a*, a bottom board, *b'*, having an opening, *a'*, corresponding with the opening *a* of the string-board *b*, and a circumferential wall, *d*, separating said string and bottom boards. The lower part, *C*, is composed of a top board, *c*, and a bottom board, *c'*, separated by a circumferential wall, *e*, and is similar to the upper part, *B*, except that the top and bottom boards are not provided with openings, but

made tight. These parts *B* and *C* are clamped together by means of screw-bolts *f*, being separated by interposed, disks *g*, whereby an intermediate space, *D*, is formed between the parts, which space is open at the sides, so that the sounds can escape more freely.

This construction of the instrument increases the volume of tone produced by the strings on the string-board, while the escape of the sound is facilitated by means of the sound-openings and the open intermediate space between the upper and lower parts. The tone of the zithern is full, sonorous, and resonant, and somewhat resembles that of the harp, so that it is adapted in a higher degree than heretofore for musical expression.

Having thus described my invention, I claim as new and desire to secure by Letters Patent—

A zithern the body of which consists of an upper part, *B*, a lower part, *C*, and means for clamping and separating said parts, whereby an open space, *D*, is formed between them, the said upper part being composed of a string-board, *b*, having an opening, *a*, a bottom board, *b'*, having an opening, *a'*, and a circumferential wall between said boards, and said lower part being composed of tight top and bottom boards and a circumferential wall, substantially as described.

In testimony that I claim the foregoing as my invention I have signed my name in presence of two subscribing witnesses.

GEORGE BENDER.
